[57] CLAIM

The ornamental design for an automobile grille, as shown and described.

DESCRIPTION

FIG. 1 is a front perspective view of an automobile grille in accordance with the present invention shown in a typical location at the front end of an automobile illustrated in phantom lines, which automobile forms no part of the subject invention; and,

FIG. 2 is an enlarged front elevational view thereof. The top, bottom, left, right and rear sides of the automobile grille are not visible during ordinary use.
